UNITED STATES PATENT OFFICE.

UMBERTO MIOZZA, OF WASHINGTON, DISTRICT OF COLUMBIA.

ELECTRIC BARBER'S SCISSORS.

Application filed September 21, 1925. Serial No. 57,684.

The object is the provision of a motor actuated scissors for barbers' use in which the drive mechanism for one of the blades is supported in a casing on the haft or handle of the second blade, and wherein the said haft or handle is also provided with finger blades whereby the device is conveniently supported and guided by the operator in a manner to conveniently, easily and accurately cut the hair.

The drawings which accompany and form part of this application illustrate a satisfactory embodiment of the improvement reduced to practice and wherein:

Figure 1 is a side elevation of the improvement with parts broken away and parts in section.

Figure 2 is a sectional view on the line 2—2 of Figure 1.

Figure 3 is a plan view of the drive wheel.

The scissors comprises the usual cooperating blades which are pivotally connected together by the usual means 2. One of the blades has a curved haft 3 which is round in cross section. The haft for the second blade is indicated by the numeral 3 and is of a materially greater length than the haft 3. The haft 3, at a desired point throughout the length thereof, is widened and the said widened portion is centrally slotted, as at 5.

The outer end of the haft 4 is integrally formed with upper and lower rings 6 and 7, respectively. These rings provide finger holds for the operator. A web 8 connects the ring 7 with the haft 4, while the ring 6, is provided with a guard finger 9. Both the haft 4 and ring 6 have angularly disposed web extensions which merge into a casing 10. One side of the casing is open and is closed by a cover plate which is removably secured thereon. In the casing 10 there is journaled on a stub shaft 11 a drive wheel 12. The wheel has peripheral teeth 13 and the periphery of the said wheel is preferably con-

caved. Pivotally connected to one face of the wheel 12, at a point adjacent to its periphery, there is one end of a pitman 14. The pitman is guided through the slot 5 and has its outer end bifurcated to provide a rounded fork portion 15. The arms of the fork have bearing openings for trunnions 16 on the sides of a tubular sleeve 17. The sleeve 17 is received over the haft 3 and is adjustably held thereon by means 18.

The drive wheel 12 has its teeth engaged by a worm 19 whose shaft 20 is journaled in suitable bearing openings in the casing 10, and the shaft 20 has connected thereto a flexible shaft 21 which is operated by a suitable electric motor (not shown).

The simplicity and advantages of the construction will, it is believed, be perfectly apparent to those skilled in the art to which such invention relates, but it is to be understood that I do not wish to be restricted to the precise details of construction herein set forth and reserve the right to make such changes therefrom as fall within the scope of what I claim without departing from the spirit of my invention.

Having described the invention, I claim:

A barber's shears or scissors having its blades formed with extending hafts, one of which is curved and the other being of a greater length and formed with outer rings providing finger receiving elements, one of said rings on said longer haft, having ribs thereon which merge into a casing, a motor driven wheel journaled in the casing, a pitman eccentrically secured to the wheel and guided through the last mentioned haft, said pitman having a forked end, a sleeve having trunnions journaled in the arms of the fork and said sleeve received on the mentioned shorter haft and removably secured thereto.

In testimony whereof I affix my signature.

UMBERTO MIOZZA.
